(57) **CLAIM**

The ornamental design for a go kart engine shipping container, as shown and described.

DESCRIPTION

FIG. 1 is a perspective view of the go kart engine shipping container of this design.

FIG. 2 is a top plan view of this device.

FIG. 3 is a front elevational view of this device. The rear face is a mirror image thereof.

FIG. 4 is a bottom plan view of this device.

FIG. 5 is a right side elevational view of the device of this design. The left side is a mirror portion of this design.

FIG. 6 is a bottom plan view of the cover portion of this design.

FIG. 7 is a top plan view of the base portion thereof.

FIG. 8 is a top plan view of the insert portion of this design.

FIG. 9 is a bottom plan view of the underside of the insert.

FIG. 10 is a front elevational view of the insert portion of this design. The rear elevation is a mirror image thereof.

FIG. 11 is a side elevation of the insert of this design. The opposite side of the insert is a mirror image thereof; and,

FIG. 12 is an exploded perspective view of the three portions of the go kart engine shipping container, wherein the broken line portions of the view are shown for illustrative purposes only and form no part of the claimed design.
